DESIGN FOR A SHOE OR SIMILAR ARTICLE

Fred J. Diamant, New York, N. Y.

Application November 15, 1945, Serial No. 123,769

Term of patent 7 years

(Cl. D7—7)

To all whom it may concern:

Be it known that I, Fred J. Diamant, a citizen of the United States of America, residing in New York, county of New York, and State of New York, have invented a new, original, and ornamental Design for a Shoe or Similar Article, of which the following is a specification, reference being had to the accompanying drawing, forming part thereof.

The figure on the drawing is a perspective view of a shoe or similar article showing my new design. The opposite side presents substantially the same appearance as the side shown.

I claim:

The ornamental design for a shoe or similar article, substantially as shown and described.

FRED J. DIAMANT.
